DAVID DAVY, OF SHEFFIELD, ENGLAND.

Letters Patent No. 78,933. dated June 16, 1868.

IMPROVEMENT IN PISTON-VALVES FOR STEAM-HAMMERS.

The Schedule referred to in these Letters Patent and making part of the same.

TO ALL WHOM IT MAY CONCERN:

Be it known that I, DAVID DAVY, of Sheffield, in the county of York, England, have invented a new and useful Improvement in Steam-Hammers; and I do hereby declare that the following is a full, clear, and exact description thereof, which will enable others skilled in the art to make and use the same, reference being had to the accompanying drawings, forming a part of this specification.

The object of this invention is to provide means for economizing steam in the use of steam-hammers, or of hammers actuated by any other elastic fluid, when such hammers are working with a varying length of stroke.

The cylinder and piston to which the hammer is immediately connected, may be constructed in any of the various forms usually adopted, but the distribution of steam or other fluid is effected as follows:

I propose using a piston-valve, with two or more pistons or valves upon the rod, but for the present purpose I will describe the one with two pistons or valves.

The steam or other fluid is admitted into the valve-chest between the two pistons, and the exhaust steam passes into the valve-chest from the cylinder at each end of the valve-chest, and from thence into the exhaust-pipe.

The pistons or valves are hollow, and around their circumference are ports corresponding with and opposite, or nearly so, with other ports in the valve-casing.

By this means when the valves or pistons are in a certain position, a communication is established between the top and bottom of the cylinder.

The valves are made to reciprocate in the casing either by hand or by a self-acting motion.

The ports in the valve-casing answer both for the ingress and egress of the steam, and for passing it from the top to the bottom of the hammer-cylinder, or *vice versa*, but the ports around the circumference of the piston-valves, and the passage connecting them together, are only used as a communication for equalizing the pressure of the steam in the top and bottom of the hammer-cylinder.

The mode of operation is as follows: Supposing the hammer is to be raised as for commencing operations, the valves will be moved in a downward direction, admitting the steam or other fluid to the under side of the piston, and when the piston has ascended sufficiently high, the valves will be moved in an opposite direction, till the equilibrium-ports in the valve are opposite the ports in the casing.

In this position a portion of the steam or other fluid which has raised the hammer will pass from the lower to the upper side of the piston, thereby equalizing the pressure on both sides of the piston, when the hammer will descend with a velocity due to gravitation alone.

When it has descended, the valves will be again reversed, the equilibrium-ports will be closed, and the steam or other fluid on the under side of the piston will be retained, in anticipation of the next stroke, whilst the steam on the upper side will be exhausted.

The steam or other fluid is then admitted for again raising the hammer.

When the steam or other fluid is to be admitted to the upper side of the piston, for accelerating the downward stroke, the action of the valves is as follows:

For this purpose the valves will be moved in a downward direction, admitting steam or other fluid to the under side of the piston, and when the hammer has ascended sufficiently high, the valves will be moved in the contrary direction, till the equilibrium-ports in the valves are opposite the ports in the casing, when the pressure in the cylinder will be equalized above and below the piston.

This operation so far is precisely the same as for the one previously described, or for the single-acting hammer, but instead of reversing the valves, as in the previous case, they will continue moving in the same direction, till the ports are open to the steam or other fluid at the top side of the piston, and to the exhaust-pipe on the bottom side.

The hammer will then descend with a velocity due to its own gravity, and the pressure of the steam or other fluid on its top side.

After it has descended, the valve will be again moved downward, and the equilibrium-passage and ports

opened, when a portion of the steam or other fluid will pass from the top to the lower side of the piston, and will be retained there until the next charging, when the steam or other fluid on the top side will be exhausted.

Instead of piston-valves, slide-valves, or conical or cylindrical valves may be used, to the latter of which I give a partial rotary motion, and provide the necessary passages for effecting the object desired.

Two or more single valves may be adapted and applied to effect the same purposes as the valves referred to in the operation already described.

My improvements for effecting the object I have in view are illustrated in the accompanying drawings, in which—

Figure 1 represents a vertical section of a hammer-cylinder with piston, and with the valve-chest and valves arranged to operate as heretofore described, the section being through the line *x x* of fig. 2.

Figure 2 is a horizontal section of fig. 1, through the line *a a*.

Figure 3 is a horizontal section of fig. 1, through the line *B B*.

Figure 4 is a longitudinal section of the valve and chest, through the line *c c* of fig. 2.

Similar letters of reference indicate corresponding parts.

Referring again to fig. 1, the steam or other fluid is admitted into the valve-casing at *a*, (see fig. 2,) and fills the annular space *b*, around the central portion between the pistons or valves *c c*, and it will be seen that when the valves are moved in a downward direction, the steam or other fluid will pass from the annular space *b*, through the port *d* to the under side of the piston, thereby raising the hammer which is attached to the rod *e* of the piston *f*, and if when the hammer has ascended sufficiently high, the motion of the valves be reversed, and brought to the position seen in the drawing, it will be seen that a communication is established between the bottom and top of the cylinder, and a portion of the steam or other fluid will pass from the under side to the top of the piston, through the ports *d* and *g* in the cylinder, by means of the equilibrium-ports in the valves.

H is the exhaust-pipe.

I is the valve-spindle, which works through a stuffing-box, and is connected with belting or levers, or a self-acting motion in the ordinary manner.

Having thus described my invention, I claim as new, and desire to secure by Letters Patent—

The hollow piston-valve, provided at the top and bottom with the valves *c c*, between which the annular space *b* is formed, arranged to operate in relation with the ports *d g* in the cylinder, the induction-port *a*, and exhaust *H*, as herein described for the purpose specified.

The above specification of my invention signed by me, this second day of December, 1867.

DAVID DAVY.
